VENTILATED SHOE

Richard R. Gantt, San Antonio, Tex.

Application November 13, 1945, Serial No. 628,041

3 Claims. (Cl. 36—3)

1

This invention relates to the art of ventilated shoes, and in its more specific aspects relates to a device which is incorporated in the heel of a shoe, and which injects a supply of fresh air to and around the foot of the wearer; and the nature and objects of the invention will be readily recognized and understood by those skilled in the arts to which it relates in the light of the following explanation and detailed description of the accompanying drawings illustrating what I at present believe to be the preferred embodiments and mechanical expressions of the invention from among various other forms, arrangements, combinations, and constructions, of which the invention is capable within the spirit and scope thereof.

It is therefore an object of my invention to provide a shoe having means therein for automatically supplying fresh air to and around the foot of the wearer.

A further object of my invention is to provide a ventilated shoe which provides a supply of fresh air to the foot of the wearer without in any way distorting the shoe so as cause discomfort to the wearer.

It is a further object of my invention to provide a ventilated shoe in which the apparatus for supplying fresh air to the foot of the wearer is disposed in the heel of the shoe.

And yet another object of my invention is to provide a ventilated shoe in which the operating elements of the apparatus for supplying fresh air to the foot of the wearer are disposed in a renewable portion of the heel of the shoe.

Another object of my invention is to provide a ventilated shoe having fresh air supplying apparatus disposed in the heel of the shoe in such a manner that no additional or undue wear will occur on the heel.

A further characteristic of my invention is to provide shoe ventilating means within the heel of a shoe which comprises few operating parts.

And a further object of my invention is to provide a ventilated shoe which is relatively inexpensive to manufacture and which may be renewed in the same manner as the present heel is renewed.

With the foregoing general objects, features and results in view, as well as certain others which will be apparent from the following explanation, the invention consists in certain novel features and designs, construction, mounting and combination of elements, as will be more fully and particularly referred to and specified hereafter.

Referring to the accompanying drawings:

Fig. 1 is a view in elevation of the invention with parts thereof broken away to show the air pumping or supplying apparatus.

Fig. 2 is a vertical section of the heel portion

2

of the shoe, with the diaphragm illustrated at the completion of the compression stroke.

Fig. 3 is a bottom plan view of a shoe with portions of the heel thereof removed.

Fig. 4 is a vertical section through the heel portion of a shoe embodying a modified form of my invention.

Fig. 5 is an enlarged view in vertical section of the valve mechanism disclosed in Fig. 4 of the drawings.

Referring to the drawings wherein like characters of reference designate similar parts throughout the several views in the drawings, I have used the numeral 1 to designate the upper 15 of a shoe and the numeral 3 to designate the usual sole thereof. The heel of the shoe, which includes the novel air pumping apparatus which will be described hereinafter, is designated by the numeral 5.

20 In order to provide the pumping apparatus with a supply of fresh air, I provide an intake duct 7 in the upper portion 1 of the shoe at the heel portion thereof. As illustrated in the drawings, such intake duct is formed to extend 25 from the upper edge of the shoe upper centrally of the heel portion of said shoe upper to the base or inner sole 10 of the shoe. The intake duct then extends horizontally below the inner sole as at 9 to a point in substantially the center 30 of the heel where it extends vertically through the upper body portion of the heel and a tube or the like 11 is disposed therein and extends therefrom to provide a tube extension 13. It will be recognized that fresh air may flow into 35 the upper end of the duct 7 for transmission into the heel through the ducts 9 and tube 11 and the tube extension or exposed end 13.

The heel 5 includes two solid plies 15 and 17 of leather or the like relatively stiff or rigid material forming the upper body or permanent portion thereof.

While the upper body or permanent portion of the heel is illustrated as being composed of two plies of leather or the like materials I do not intend to so limit my invention, for such upper body may be formed of only one ply, or if found desirable it may comprise more than two plies, I do, however, desire to point out that the upper body of the heel, in the illustrated 45 embodiment, the plies 15 and 17 should provide a comparatively rigid support for the heel of the wearer of the shoe, a support with substantially no "give" or flex under the weight of the heel of the wearer. The specific reasons and advantages of such construction will become apparent 50 as the specification proceeds.

Attached in any desirable manner to the lowermost ply 17 of the upper body portion of the heel is a member or bridge 19 of inverted cup 55 shape to provide a downwardly extending flange

60 shape to provide a downwardly extending flange

21. The bridge member 19 as may be clearly recognized by referring to the drawings is of reduced proportions relative to the plies 15 and 17 and is formed of a relatively stiff rigid material such as leather. The vertical section 11 of the intake duct extends through the plies 15 and 17 and the tube extension 13 of tube 11 extends through member 19 to project downwardly to be free thereof.

Metal, plastic or the like spacers 23 and 25 comprising longitudinally elongated strips, are secured to member 19 on each side of the intake tube extension 13. Such spacers are of sufficient depth to project downwardly from member 19 a distance greater than the free or exposed end of tube extension 13.

The body or ground contacting portion of the heel, which, as will become apparent herein-after, forms the air pumping device or diaphragm of my invention is composed of a member of substantially cup shape which is indicated generally by the numeral 21. This cup shaped member is composed of a central ground contacting body portion forming a diaphragm 29 and a flange 31 which extends about the central body portion or diaphragm and, when the cup shaped member is applied in position on the heel the flange 31 embraces within the confines thereof the downwardly projecting flange 21 of member 19, and is in contact therewith. It will be readily recognized that cup shaped member, or lift 21 is secured to the heel by attaching the flange 31 to ply 17 and by attaching the contacting surfaces of the two flanges together. Since flanges 21 and 31 are of substantially the same depth it will be apparent that flange 21 will engage the upper surface of the diaphragm portion 29 of member 27 adjacent to the edge thereof.

By the novel construction, mounting and combination of members 19 and 27, an air reservoir, cavity or chamber 28 is provided between said two members, and into this reservoir the fresh air intake duct empties, and the exposed end 13 extends, as do spacing elements 23 and 25.

I preferably form member 27 of rubber or the like material, so that it will possess the quality of flexibility. The member 27 may be molded or otherwise formed to provide a bulge in the central body portion or diaphragm 29 thereof, so that the normal position thereof is as illustrated in Fig. 1 of the drawings, with the diaphragm flexed outwardly away from the remainder of the heel.

A deformable live rubber or the like stopper or valve 33 is mounted on and carried by the inner surface of diaphragm 29 to extend into the air reservoir, in position thereon disposed directly below the tube exposed end or extension 13, and a leather washer 35 is secured on top of the stopper or valve element 33. It will be noticed that the top of the valve is spaced from the extension 13 when the diaphragm is in downwardly flexed or normal suction stroke position.

An exhaust duct 37 extends from air reservoir 28 upwardly through plies 15 and 17 and member 19. The intake of the exhaust duct from the reservoir is regulated by a valve 39 which in this particular instance is illustrated as being normally retained in duct closing position by means of a weight 41. The exhaust duct extends horizontally forwardly of the shoe beneath the inner sole thereof as at 43 and is branched or forked at its forward end as at 45 and 47, the ends of the branches opening into the in-

terior of the shoe as at 49 to inject fresh air thereinto and about the toes and foot of the wearer. It will be obvious that the exhaust duct may have any number of branches emptying into the shoe at various points without departing from the spirit and scope of my invention.

The pumping apparatus carried in the removable or lower part of the heel is illustrated in Fig. 1 of the drawings with the diaphragm 29 at the end of its suction stroke which occurs when the wearer is walking and the foot is lifted from the ground. As hereinbefore stated the lift or ground engaging portion 27 of the heel is molded or otherwise formed so that the diaphragm portion 29 is normally in extended or suction stroke position. When the foot is lifted from the ground the diaphragm will move into the position of Fig. 1 of the drawings and fresh air will be drawn into and through the intake ducts 7 and 9, tube 11 and extension 13 and into reservoir 28, valve 39 closing exhaust duct 37 immediately the suction stroke is commenced, hence the reservoir will be filled with a supply of fresh air. As the wearer steps down on the shoe the diaphragm will be compressed and the compression stroke thereof will be effected. The air pressure within the reservoir, upon diaphragm compression stroke, will open valve 39 so that fresh air may flow into the shoe interior through exhaust ducts 37, 43, 45, and 47. Consideration of the drawings, and particularly Fig. 2 thereof, shows the valve 33 will engage the free or exposed end of intake tube 11 before the diaphragm completes the compression stroke, and will be deformed thereby to contract about tube end 13 to completely close such tube against the admission of any air under pressure from the reservoir. The compression stroke of the diaphragm is completed when the diaphragm comes into contact with spacers 23 and 25 which are constructed in a manner to protect valve 39 from contact with the diaphragm, and to restrain the diaphragm on the compression stroke from extending far enough into the reservoir to snap upwardly thereinto, instead of automatically returning to its flexed suction stroke position.

Upon normal wear of the heel as occurs in every shoe the members 19 and 27, which form a unit, may be renewed. Now it is important to understand that all of the operating elements are mounted in the renewable unit and hence no annoyance or difficulty is experienced in attaching a new heel to the shoe.

The renewable heel units are produced with the pumping apparatus and the ducts therein and the individual shoe repairman merely attaches such unit to the ply 17, the duct therein mating with the ducts in plies 15 and 17.

It is significant to recognize my particular construction of heel whereby the ventilating effect is attained by the pumping apparatus disclosed therein without in any way causing discomfort to the foot of the wearer of the shoe. In order for a shoe to be comfortable at the heel portion thereof, it is essential that the foot or heel of the wearer retain static contact with the bottom of the shoe, in other words, it is important that the innersole and the structure disposed therebelow be substantially constantly in snug contact with the heel of the wearer. This requirement is completely and satisfactorily met by my structure. I dispose all of the pumping apparatus, including the movable diaphragm and the reservoir, within the bottom of the heel, and between such elements

and structure and the heel of the wearer there is a substantially stiff or rigid support for the heel of the wearer, comprising the plies 15 and 17, as well as the member 19. Hence it will be recognized that constant engagement between the heel of the wearer and the heel of the shoe will result from my novel structure and no rubbing, chaffing or the like will occur.

A further important factor which operates towards a satisfactory heel is the particular structure of member 19 having flange 21 which provides a hinge or fulcrum point from which the diaphragm reciprocates. This arrangement forms a support for the diaphragm and thereby reduces the wear on the diaphragm as well as on the entire lift, renewable or ground contacting portion of the heel.

In Figs. 4 and 5 of the drawings, I have illustrated a further embodiment of my invention and I have designated elements which are similar to those in the preferred embodiment of my invention with the same reference numerals, and since their operation and function is the same as in the preferred embodiment of my invention I will not now again describe them in detail. In this modification of my invention, I provide an intake duct 51 extending through the rear portion of the heel plies 15 and 17 and the member 19 for supplying fresh air to the pumping apparatus. A horizontally disposed section of the intake duct is designated by the numeral 53, this horizontal section extends through the flange 21 of member 19 to empty into the reservoir 28 provided in the heel. Instead of the deformable valve 33 of the preferred embodiment of my invention, I utilize a hinge-type gate valve 60 which is hinged as at 59 to the flange 21 to extend over the mouth of the intake duct 53 for the regulation of the supply of fresh air. The valve itself comprises a metal portion 55 and a leather washer facing 57. It will be obvious that the metallic portion of the valve provides sufficient weight to dispose the valve in closed position under certain operating conditions.

I provide a vertically disposed exhaust duct 61 which extends upwardly from the reservoir 28 through the plies 15 and 17 to connect with the sole duct 43 for transmitting a supply of fresh air to and around the foot of the wearer of the shoe. Such duct 61 is substantially one-third the diameter of the intake duct 51 for a purpose which will hereinafter be made clear.

When the diaphragm 29 is on the suction stroke the valve 60 is in open position due to the suction and air pressure applied thereto, to thereby cause a flow of fresh air to enter the reservoir through the ducts 7a and 51. When the wearer steps upon the heel and the diaphragm is on its pressure stroke, the valve 55 is closed and air is forced through the ducts 61 and 43 to flow about the foot of the wearer. It will be noticed that I do not utilize a valve in the exhaust duct in this form of my invention. However, it will be understood that when pressure is removed from the shoe and the diaphragm is in its suction stroke, the air will rush in from both the intake and exhaust duct, but since ducts 51 and 7a are substantially three times the diameter of duct 61, it will be evident that a greater volume of air enters through duct 51 than through duct 61. Thus a greater volume of fresh air than stale air is circulated by this particular form of my invention.

I claim:

1. Ventilating means for a shoe, comprising a heel having a cavity in the lower portion thereof,

75

substantially rigid foot supporting means disposed between the cavity and the inner sole of the shoe, an air intake tube projecting into the cavity and an air exhaust duct opening into the cavity, a flexible ground contacting lift portion of the heel, having in normal position a centrally disposed downwardly extending bulge therein, and control means for regulating the flow of air into the cavity, including an intake tube control member

10 mounted on said flexible ground contacting lifting portion for movement therewith to engage the projecting portion of said air intake tube to close the same on the compression stroke of the flexible ground contacting lift portion.

2. Ventilating means for a shoe, comprising a heel having a cavity in the lower portion thereof, substantially rigid foot supporting means disposed between the cavity and the inner sole of the shoe, an air intake tube projecting into the cavity and an air exhaust duct opening into the cavity, a flexible ground contacting lift portion of the heel, having in normal position a centrally disposed downwardly extending bulge therein and control means for regulating the flow of air into the cavity, including a deformable tube control member

20 mounted on said flexible ground contacting lift portion for movement therewith engaging and contracting about the projecting portion of said air intake tube to close the same on the compression stroke of the flexible ground contacting lift portion.

3. In a shoe provided with a heel, said heel comprising an upper substantially rigid permanent portion and a lower renewable portion, said 35 portions being removably attached together, said renewable portion including a flat member having a downwardly directed flange projecting from the marginal parts thereof, the member being of reduced dimensions relative to the permanent portion of the heel and removably secured to said permanent portion, and a flexible ground contacting portion having an upwardly directed marginal flange engaging and secured to said permanent portion and embracing and secured to said flange of said flat member, to provide a cavity 40 between the flat and flexible members, said flexible member having, in normal position, a centrally disposed downwardly extending bulge therein, means for admitting and releasing air from the cavity under the action of the flexible member, and control means mounted within the renewable heel portion for regulating the flow of air 45 into and out of the cavity.
